UNITED STATES PATENT OFFICE.

CHARLES OTIS PALMER, OF CLEVELAND, OHIO.

MINING-MACHINE.

1,149,215.

Specification of Letters Patent. Patented Aug. 10, 1915.

Application filed March 11, 1909. Serial No. 482,750.

To all whom it may concern:

Be it known that I, CHARLES O. PALMER, a citizen of the United States of America, and a resident of Cleveland, in the county 5 of Cuyahoga and State of Ohio, have invented certain new and useful Improvements in Mining-Machines, of which the following is a specification.

My invention relates to improvements in 10 mining machines, and the same as herein described are shown as applied to a machine of the power driven pick type.

The objects of my invention are especially to provide improved means of setting 15 and holding the carriage that carries the pick body and the frame upon which the carriage travels.

The chain mining machines now generally used have a stationary frame on which slides 20 the traveling frame that carries the cutting mechanism including the electric motor. The rear end of the stationary frame is supported by a floor rail, and is held in place, when in operation, by a jack on the forward end of the frame which is forwardly braced against the coal, and one at the rear end which is braced against the roof. These jacks take the entire thrust of the machine 25 independently of the floor rail. The floor rail is used principally because it is easier 30 to slide the machine sidewise on the rail than it would be on the rough floor. This method of placing the jacks is not applicable 35 to pick machines because the forward jack is directly in front of the machine and so is in the way of the pick. Also the rear jack is in the way of the operator who usually sits behind the pick to direct it.

My method is to hold the floor rail in 40 place (preferably by a couple of jacks J, one on each side of the machine, see Figure 3) and to detachably attach the stationary frame or platform to the floor rail so that the floor rail takes the recoil of the pick.

45 With the present pick mining machine now generally used the recoil of the pick is taken principally by a block on the foot of the machine operator which presses one of the machine wheels on the rear side and slides on the platform. The operator at the same time slues the machine around on the platform to the desired position. This is

a severe tax on the strength of the skilled operator and much more so on the unskilled one.

55

In the accompanying drawings, Fig. 1 is a side view of a pick mining machine embodying my invention taken on line 1—1 of Fig. 2 and as seen in the working position in the mine; Fig. 2 is a plan of the machine 60 taken on line 2—2 of Fig. 1; Fig. 3 is a rear view taken on the section line 3—3 of Fig. 2 and with jacks at the sides of the machine; Fig. 4 is a section on line 4—4 of Fig. 2 on a larger scale; Fig. 5 is a section on a larger scale taken on line 5—5 of Fig. 6, showing the opposing latches in their cage; Fig. 6 is a section on line 6—6 of Fig. 5; Fig. 7 is a top view of the latch cage shown in Fig. 5; Fig. 8 is a side view 70 of one of the latches shown in Fig. 5; Fig. 9 is a section on line 9—9 of Fig. 8; Fig. 10 is a side view of the rail clamp shown in plan in Fig. 1 gripping the rail; Fig. 11 is a section on line 11—11 of Fig. 10 also 75 showing the rail clamp when turned to the backward or disengaged position; Fig. 12 is a side view on a larger scale of the jack shown in Fig. 3; Fig. 13 is a rear view of the jack shown in Fig. 12; and Fig. 14 is 80 a top view of the jack saddle.

65

The same characters of reference designate the same parts throughout the several views.

As shown in Figs. 1, 2, and 3 a rail 21 of 85 wood (or iron) is laid on the floor of the mine parallel with the working face of the coal and several feet from it. It is held in place by a couple of jacks J that are braced against the mine roof (or by other suitable 90 means). Said floor rail 21 supports the rear end of the stationary frame F while its forward end rests on the floor itself. The frame F is held in place by being clamped to the floor rail 21. The carriage 95 C travels on said frame F, and the yoke Y swivels vertically on the carriage and supports on horizontal trunnions 27 the machine body B that contains the mechanism for operating the pick PK. The operator 100 sits on the frame or platform F back of the machine body and directs the blows of the pick by the handles H; the power for driving the pick being derived from an air com-

pressor (not shown) through the tubes F^1 and F^2 (or by any other suitable means). After cutting a kerf having a floor surface about 4 by 5 feet, the track clamps T are loosened and the machine is moved sidewise about four feet and again clamped for another cut, and so on to the end of the working face of the coal.

The frame F is composed of an iron plate 30 to prevent lateral distortion and form an iron surface to stand the wear of the carriage rollers 22, and a wood planking 31 on its upper side to afford longitudinal rigidity and to cover said plate so that the operator shall not have a cold iron seat when directing the pick. These planks moreover form a continuous elevated platform above the rack R whereon the operator may conveniently sit in the various positions of longitudinal adjustment of the machine carriage and body. I also prefer to back the under side of the plate by the planks 32 so as to further stiffen it transversely. These frame parts are held together by the bolts 33. The track also has a rack R extending longitudinally over part of its length and is held by the bolts 34.

The carriage C is provided with rollers 22 that rest on the plate 30 and with lips 23 that engage with the groove 35 of the track to prevent vertical and lateral displacement. The track being flat to save height is not well adapted to resist the torsion produced by the action of the pick. To allow a free motion of the carriage C on the track, the rear wheels are journaled on the lever S that is hinged on the pin 96 that lies lengthwise of the track and so allows the wheels to adjust themselves to the track even if the track is warped.

The rail clamp T has a gap on its lower side that straddles the floor rail 21 (see Fig. 10). It is here shown as provided with a screw 24 to take up any lost motion between the saddle and the rail. The upper end of clamp T is hinged to the frame F by the screw 25 that is held in the bearings 26 on either end. When not in use the clamp is turned back to the position shown in dotted lines in Fig. 11. The lower side of the frame F then presents a clear smooth surface which facilitates loading the machine on the truck (not shown). If the clamps T , T could not be turned backward but were in continual sliding engagement with the floor rail when moving from setting to setting it would be necessary to move both ends of the frame F at once which would be difficult for one man to do. But by turning the clamps backward clear of the floor rail, one end of the frame may be moved at a time independent of the other end. Also by having the clamps T , T adjustable lengthwise of the frame F it allows a considerable latitude in setting the frame on the floor

rail, as it is but a small matter to adjust the clamp longitudinally to suit the position of the frame, which is done by rotating the screw 25 by the knob on its end.

Sliding on the rack R is the latch cage L 70 that is attached to the carriage C by the latch rod 40 (Figs. 1 and 2). Hinged in said frame L are the opposing latches 94 and 95. Each latch or click engages the rack and prevents motion of the carriage in 75 one direction only. That is, the latch 95 prevents a backward movement and the latch 94 a forward movement of the carriage. To move the carriage forward lift the latch 94 out of engagement with the 80 rack (as shown in Fig. 5) and push forward. To move the carriage backward disengage the latch 95 and pull backward.

The advantage of two opposing latches, I will now explain. In my mining machine 85 Patent No. 800479 the carriage was held in position by a bolt, that prevented motion along the track in either direction, so that when the bolt was withdrawn from engagement with the track the vibration or recoil 90 of the machine was taken by the machine operator. As is well known this recoil is one great drawback to the reciprocating pick as now made. I have overcome this difficulty by having two opposing latches, 95 one 94 allowing a backward movement only and the other 95 allowing a forward movement only of the carriage. Thus by a momentary disengagement of the latch 94 advantage may be taken of the forward 100 impulse of the carriage to assist in moving it forward while the latch 95 engages the rack and prevents any possible backward movement. Likewise advantage may be taken of the backward impulse or recoil of the carriage 105 to assist in moving the carriage backward, by disengaging latch 95 while latch 94 still engages the rack and prevents a forward movement of the carriage.

Under ordinary conditions when the 110 track is nearly level and the pick in operation, the reciprocating impulses imparted to the cylinder are strong enough to move the carriage along the track in either direction with little or no help from the operator. But when the pick is not in operation it requires a very strong pull to manually move the carriage along the track.

Although the floor rail may be held in place by an ordinary jack braced between it 120 and the roof, I prefer the arrangement shown in detail in Figs. 12, 13 and 14. As here shown a hole is made in the floor beside the rail 21 by a few strokes of the pick. The lower end 53 of the jack J is flattened 125 to fit this hole. The jack saddle 51 straddles the floor rail 21 and has a hole through one of its sides to admit the stem 50 of the jack J . The nut 52 engages the thread on said stem and also the saddle 51 which it presses 130

5 downward against the floor rail 21 with as much pressure as deemed necessary to hold it in place. By this means the floor rail is held in place on the floor more securely and the jack is held in place more firmly by being pressed into a hole in the floor than if I depended upon the friction against the floor to hold them in place.

10 It is evident that a rod may be used instead of the screw 25 and the clamp T secured in place on it by a set screw or otherwise. But the screw is more liable to prevent the clamp T slipping lengthwise on it, and this is the direction of greatest stress 15 tending to move it.

15 The tool as shown in Fig. 1 is intended for cutting the ordinary horizontal kerf. When built for cutting a vertical kerf or shearing as it is called, the swivel connection between the yoke Y and the carriage C 20 may be omitted and the yoke formed directly on the carriage C.

25 I do not wish it understood that I am limited to the form of floor rail here shown or to the means here shown for securing the frame and floor rail together; as others will readily suggest themselves to those skilled in the art.

30 I have not in this application broadly claimed the jack screw and saddle herein set forth as the same form the subject of my separate application for a jack for mining-machines, Serial No. 792,096, filed Sept. 27, 1913.

35 Having set forth my invention, I claim:

1. In apparatus of the class described, the combination with a supporting rail, of screw mechanism for securing the same to the floor, a machine frame supported upon 40 said rail, hinged clamps adapted to engage the said frame and supporting rail and secure the frame at any point thereon, a carriage mounted upon the frame, and a machine body supported by said carriage, substantially as set forth.

2. In apparatus of the class described, the combination with the floor rail, of means for securing the same in position upon the floor of the mine, a machine frame supported on 50 said rail, hinged clamps attached to said frame and adapted to engage the rail, and a mining machine mounted upon said frame, substantially as set forth.

55 3. In a mining machine the combination of a floor rail, a machine frame supported crosswise on said rail, jacks holding said rail, hinged clamps longitudinally adjustable on the sides of said frame and engaging the floor rail, a carriage mounted on said frame and a machine body positioned thereon.

60 4. In apparatus of the class described, the combination with a floor rail, of means for securing the same in position upon the floor of the mine, a machine frame supported on

said rail, hinged clamps upon the frame, means for longitudinally adjusting the clamps with respect to the frame, and a mining machine mounted upon said frame, substantially as set forth.

70 5. In a mining machine of the class described the combination with the supporting rail, of jack mechanism for securing the same to the floor of the mine, a machine frame supported by the rail, hinged clamps upon said frame adapted to engage the rail and secure the frame at any desired point thereon, a carriage mounted upon the frame and a machine body supported by the carriage, substantially as set forth.

75 6. In apparatus of the class described, the combination with a stationary frame, of a machine carriage movable thereon, a longitudinal rack positioned upon said frame, and two oppositely acting clicks connected to 80 the carriage and adapted to engage the rack, substantially as set forth.

85 7. In a mining machine the combination of a stationary frame, a machine carriage on said frame, a rack extending lengthwise 90 of said frame, a latch-cage attached to said carriage, two opposing latches pivoted in said latch-cage and engaging said rack.

90 8. In a mining machine the combination of a stationary frame, a machine carriage 95 movable on said frame, a rack extending lengthwise of said frame, a latch-cage attached to said carriage, two opposing latches pivoted to said cage and engaging said rack, said latches being hinged at the extremities 100 of said cage and lips on the under side of said cage engaging the rack.

105 9. In a mining machine the combination of a floor rail, a machine frame supported on said rail, jacks for holding said rail, longitudinally adjustable rail clamps on the sides of said frame and engaging the floor rail, a carriage adapted to run on said frame, a reciprocating pick and body mounted thereon, a rack extending lengthwise of 110 said frame, a latch-cage attached to said carriage and one or more latches on said latch-cage for engaging said rack.

115 10. In apparatus of the class described, the combination with a floor rail, of a machine frame adapted to rest crosswise on said rail, hinged clamps attached to the frame and adapted to engage the said supporting rail and secure the frame at the desired point thereon, a carriage mounted 120 upon the frame, a reciprocating pick body mounted on said carriage, a rack extending longitudinally of said frame, and two oppositely acting clicks operatively connected with the carriage and adapted to engage the 125 rack, substantially as set forth.

130 11. In apparatus of the class described, the combination with a stationary frame, of a carriage movable thereon, a rack extending longitudinally of said frame, mechanism

attached to said carriage and engaging said rack, said mechanism consisting of a click controlling the forward movement only of said carriage, and a second click controlling the backward movement only of the carriage along said track, substantially as set forth.

Signed at Cleveland this 25th day of Feb'y 1909.

CHARLES OTIS PALMER.
